United States Patent Office

Des. 192,812
Patented May 15, 1962

192,812

CULINARY BEATER

James L. Hvale and Robert A. Eckersberg, Chicago, Ill., assignors to Ekco Products Company, Chicago, Ill., a corporation of Delaware

Filed Apr. 17, 1961, Ser. No. 64,781

Term of patent 14 years

(Cl. D44—1)

FIG. 1 is a front elevation of a culinary beater showing our new design.

FIG. 2 is a fragmentary side elevation of the article as it appears from the left side of FIG. 1.

FIG. 3 is a fragmentary side elevation of the article as it appears when viewed from the right of FIG. 1.

FIG. 4 is a top plan view thereof.

The essential features of our design reside in the portion shown in solid lines on the drawings.

We claim:

The ornamental design for a culinary beater, as shown and described.
